UNITED STATES PATENT OFFICE.

ROBERT HEAD, OF NEW YORK, N. Y., ASSIGNOR TO THE AEOLIAN COMPANY, A CORPORATION OF CONNECTICUT.

AUTOMATIC STOP FOR PHONOGRAHS.

1,358,312.

Specification of Letters Patent.

Patented Nov. 9, 1920.

Application filed October 21, 1918. Serial No. 253,958.

To all whom it may concern:

Be it known that I, ROBERT HEAD, citizen of United States, residing at city, county, and State of New York, have invented new and useful Improvements in Automatic Stops for Phonographs, of which the following is a specification.

My present invention relates to an improved automatic stop for phonographs and 10 the like adapted to stop the instrument when the stylus reaches the end-groove of the record and to do this automatically without previous setting of any part at said groove.

In the drawings, illustrating one of the 15 specific embodiments my improved stop is adapted to take, Figure 1 is a plan view of the record, turn-table, tone-arm, sound-box, etc., of a phonograph equipped with my automatic stop, showing the brake "off" 20 with the sound-box approaching the middle of the record; Fig. 2 is a plan view of the base-plate detached from other parts of my stop; Fig. 3 is a plan view of the pivot-plate, brake-lever, latch-arm and spring 25 detached from the aforesaid base-plate; Fig. 4 is a side elevation of my stop as viewed from the left in Fig. 1; Figs. 5, 6 and 7 are vertical sections partly in elevation respectively on the lines 5-5, 6-6, and 7-7 in Fig. 1 looking in the direction of the arrows; Figs. 8, 9 and 10 are diagrammatic plan views of the lower end in Fig. 1 of my automatic stop to indicate the different positions assumed by the parts during playing (Figs. 30 35 and 9) and also at the moment before the brake-lever is automatically tripped (Fig. 10); Fig. 11 is a plan view like Fig. 1 except that the parts are positioned with the sound-box stylus in the end-groove of the record 35 and with the brake automatically "tripped" 40 and against the turn-table; and Fig. 12 is the same as Fig. 1 except that the parts of the stop are positioned as they will be when the sound-box is at the beginning part of 45 the record to illustrate the further feature of the stop whereby the act of holding the sound-box stationary at or near the beginning of the record will not automatically trip the brake although it will do so at the 50 end of the record as will hereafter appear.

I will now describe the illustrated preferred embodiment of my invention in connection with the related phonograph-parts. 55 1 is the rear-wall and 2 the deck of the phonograph-cabinet; 3 is the tone-arm, 4

the sound-box, and 5 its stylus. 6 is a disk-record on the turn-table 7. Both the record and turn-table are broken away in Figs. 1, 60 11 and 12 to show the structures lying under the turn-table including the motor-driven spindle 8 supporting the turn-table (cf. Fig. 5) together with the parts making up my automatic stop.

Said stop comprises a base-plate 9 shown 65 separately in Fig. 2 stationarily secured to the deck 2 of the phonograph in the position shown in Fig. 1 under the turn-table. The lower end 10 of this base-plate is vertically up-turned (cf. Fig. 4) and is extended to the 70 left to provide a support for the horizontal pin 11 on which is rotatably mounted the gear-wheel 12 having the lugs 13-13. The particular gear-wheel shown happens to have eight teeth with two lugs 13 on it 180° apart. 14 is a sleeve fixedly surrounding the 75 turn-table or motor-spindle 8 and is formed at its upper end with a screw-thread 15 which meshes with the gear-wheel 12, each complete rotation of the spindle 8 rotating the gear-wheel one tooth in clockwise direction in Fig. 5.

16 is a pivot-plate on top of the base-plate and pivoted thereto at 17. (18 is a hook-shaped lug on the base-plate projecting through an opening 19 in lower end of the pivot-plate and overlying the pivot-plate beyond said opening so as to hold the pivot-plate down on the base-plate and yet permit 85 it to pivot laterally thereon about the aforesaid pivot 17). 20 is an elbow-shaped brake-lever pivoted at 17 on the same pivot-pin that pivots the aforesaid plate 16 to the base-plate 9. 21 is an up-turned lug on this brake-lever carrying the usual leather or felt brake-shoe 22 adjacent the rim of the turn-table. 90

23 is a piece of spring wire having its middle portion supported on the pivot-plate 16 by the upstanding lugs 24-24 of said 100 plate. The tensioned bent upper end 23^a of this wire bears against the notched left-hand end of the brake-lever 20 (cf. Fig. 4) and serves to pivot the brake-lever into braking position as in Fig. 11 whenever it is unlatched.

The means for latching the brake-lever in its "off" position as in Fig. 1 consists of the rod 25 pivoted at 26 to the left end of the brake-lever and extending through a 110 vertically elongated eye or hole formed in a lug 27 upstanding from the pivot-plate 16

(*cf.* Fig. 4). There is a notch 25^a (Fig. 4) in the lower side of this rod 25 which, when the brake is "off," gravitates down over the lower edge of the eye in the aforesaid lug 5 27 and thereby latches the brake in its "off" position shown in Figs. 1 and 4.

The tip of this latch-rod 25 projects far enough toward the gear-wheel 12 so that whenever lug 13 happens to be at the left 10 side of the wheel, as it rotates, will on occasion underlie and lift said tip of the latch-rod, thereby unlatching its notch from the lug 27 to permit the spring 23 to apply the brake.

15 28 is an upstanding downwardly beveled lug or toe on the free end of pivot-plate 16 with which bevel each lug 13 on the rotating wheel 12 contacts as it rotates downwardly along with the right-hand side of the wheel 20 (Fig. 1, 8, and 10) so that twice in every rotation said wheel swings the plate 16 to the right about its pivot 17, each time into the position shown in Figs. 8 or 10. Note from said Fig. 10 that this right-hand position of the pivot-plate is the one which carries the latch-rod into the upward rotary path of the particular lug 13 that has just cammed the plate over to the right so that it will unlatch said rod and apply 25 the brake unless meanwhile the pivot-plate has been swung over into its left-hand position of Figs. 1 and 9.

During the playing of the record, the lateral travel or feed of the sound-box and tone-arm across the record is the motive-force which is used to swing the pivot-plate 16 to the left immediately after each time it has been swung to the right by the lugs 35 13-13. To this end, a crank-arm 29 is provided on the rotary vertical portion of the tone-arm (Fig. 1) connected by a link 30 with a strip 31 which latter is lengthwise slotted at 32. The free end of this strip is slidably guided in a slot 33 (*cf.* Fig. 5) 40 in the up-turned lower end 10 of the base-plate 9. 34 is a pin projecting upwardly from the brake-lever through the slot 32 in the strip 31. 35 is a leaf-spring riveted at one end 36 to the brake-lever and at its 45 other side presses the strip 31 frictionally against the brake-lever so that as the crank-arm 29 constantly swings (downwardly in Fig. 1) during the normal feed of the sound-box and tone-arm across the record, it slides the strip 31 downwardly and in turn swings the brake-lever 20 slightly about its pivot 17 due to the frictional grip of the aforesaid leaf-spring 35. The upward swing thereby delivered to the left-hand end of said brake-lever (Fig. 1) is 50 delivered by the latch-rod 25 to the pivot-plate 16 whose lower end as a result swings to the left. In short, the sound-box as it feeds 55 during playing toward the center or last groove of the record and until it reaches

said last groove is constantly tending to swing the pivot-plate 16 toward the left,—compare Figs. 1 and 9;—this being the normal condition existing between the intervals when as previously explained twice during each rotation of the gear 12, the lugs 13-13 forcibly swing the pivot-plate 16 to the right without, however, interfering with the playing feed of the sound-box across the record because the frictional grip of the aforesaid leaf-spring 35 is purposely so slight that the brake-lever 20 slips on the strip 31 without checking or interfering with the continuous feed of the sound-box 75 across the record.

The operation of the device can now be understood. The operator will first swing the sound-box to the right beyond the edge of the turn-table. This will pull the slide 85 31 upwardly which in turn will automatically pull the brake-lever 20 into its "off" position due to the lower end of the slot 32 in said slide carrying against the pin 34 of the brake-lever. Incidentally, this will 90 put the spring 23 under tension with the brake-lever 20 latched by the rod 25 to the pivot-plate 16. Also, this latching back of the brake will start the motor to rotate the turn-table and record and will also drive 95 the gear-wheel 12 from the screw 15. Next, the operator will swing the sound-box to the left and lower the stylus into engagement with the beginning of the record and the playing will begin and proceed as in Fig. 100 1, the pivot-plate 16 being incidentally swung to the left until stopped in the position shown in Fig. 1. The gear-wheel 12 rotates in clockwise direction in Fig. 5 and each time one of its lugs 13 rotates downwardly with the right side of the wheel it cams the beveled-toe 28 and pivot-plate 16 to the right, *viz*: into the position shown in Fig. 10 whereby the tip of the latch-rod 25 is also swung to the right into a position which, if maintained, would result in unlatching the brake and stopping the playing, because the continued rotation of the given lug 13 would cause it to strike up under the tip of said latch-rod and would 105 unlatch it and the brake-lever from the pivot-plate 16. However, this never happens until the stylus reaches the last closed-ring groove of the record, because prior to that time the sound-box stylus and tone-arm 110 are being constantly fed toward the center of the record by the spiral record-groove. This delivers a constant push (downward in Fig. 1) on the slide 31 which (acting through the brake-lever 20 latched by the rod 25 to the pivot-plate 16) swings said pivot-plate 16 to the left into the position shown in Figs. 1 and 9 wherein the tip of the latch-rod 25 is no longer in the path of the lugs 13 and cannot be tripped. Thus, 115 the feed of the sound-box across the record 120 125 130

constantly undoes the work of the lugs 13 by swinging the latch-rod out of the way each time one of the lugs swings it into its rotary path. This continues until the last record-groove is reached, whereupon the stylus travels around in a circle without advancing the tone-arm, so that the pivot-plate 16 and latch-rod 25, when next cammed to the right by one of the lugs 13, remains in that position (Figs. 8 and 10), so that further rotation of said lug causes it to strike up under the latch-rod, thereby unlatching it and the brake-lever 20, whereupon the spring 23 applies the brake and stops the instrument automatically after the record has made a few rotations with the stylus in the end-groove.

Thus the mere stopping of the feed of the sound-box for a few rotations of the record will automatically apply the brake. This makes the distance of the final groove from the center of the record immaterial. The device will automatically stop the record, whether long or short, at its last groove wherever located. Similarly, holding the sound-box stationary off the record will automatically throw on the brake after a few turns; and since this holding of the sound-box is often necessary in order to exercise due care in engaging it with the beginning of the record, I have made the lower end of the slide 31 wider than its middle portion, so that said wider lower end will engage the tail 23^b of the spring 23 when the sound-box is on or near any of the beginning grooves of the record. This, as shown in Fig. 12, keeps the pivot-plate 16 and latch-rod 25 yieldingly pressed to the left so that even if the sound-box be held stationary at or near the beginning of the record, the spring 23^b will nevertheless counteract the work of the lugs 13, each time they set the tip of the latch-rod in their path. After the sound-box stylus has played the first part of the record, then the slide 31 has been pushed down as in Fig. 1 until the spring 23^b no longer bears against the edge of the slide 31, and therefore will not interfere with the automatic stopping of the instrument when the last record-groove is reached.

Of course, modifications may be made in the foregoing embodiment of my invention without departing from the spirit either of said invention or of the annexed claims.

55 What I claim is:

1. In combination with a sound-reproducing machine having a motor-driven record-support and traveling sound-reproducer, an automatic stop comprising a pivoted-member pivoted at one end and having a toe at its other end; a brake-lever extending transversely of the pivoted-member and at a middle point of said lever being pivoted thereto; a latch-member connected to one end of the 60 brake-lever and adapted to be latched to the

pivoted-member to latch the brake-lever in non-braking position, at which time the free-end of the latch-member is located in adjacent spaced relation to the toe of the pivoted member; a spring acting upon the 70 brake-lever to throw-on the brake whenever the brake-lever is unlatched; a motor-driven rotary-part related both to the toe of the pivoted-member and to the free-end of the latch-member so that said rotary-part in 75 each rotation cams aside the pivoted-member to bring the free-end of the latch-member into a position wherein further rotation of said part causes it to strike against the latch-member to unlatch the brake-lever; 80 and means driven by the sound-reproducer as it plays across the record which yieldingly swings the pivoted- and latch-members back into the position from which they are cammed as aforesaid by the rotary-part. 85

2. In combination with a sound-reproducing machine having a motor-driven record-support and traveling sound-reproducer, an automatic stop comprising a laterally movable-member having a toe; a brake-lever 90 movably connected with said laterally movable member; a latch-member arranged to latch the brake-lever to the laterally movable-member in non-braking position, said latch-member extending in adjacent spaced 95 relation to the toe of the laterally movable member; a spring which impels the brake-lever into its braking position when the latch-member is unlatched; a motor-driven rotary-part related both to the toe of the 100 laterally movable-member and to the adjacent part of latch-member so that said rotary-part in each rotation cams aside the laterally movable-member to bring the latch-member into a position wherein further rotation of said part causes it to strike against the latch-member to unlatch the 105 brake-lever, and means driven by the sound-reproducer as it plays across the record which yieldingly moves the laterally movable- and latch-members back into the position from which they are cammed as aforesaid by the rotary-part. 110

3. In combination with a sound-reproducing machine having a motor-driven record-support and traveling sound-reproducer, an automatic stop comprising a vibratory-member; a brake-member movably connected with said vibratory-member; a latch-member arranged to latch the brake-member to 120 the vibratory-member in its out-of-braking position; said latch-member extending in adjacent relation to the aforesaid vibratory-member; means which impels the brake-member into its braking-position when the 125 latch-member is unlatched; a motor-driven rotary-part related both to the vibratory-member and to the latch-member so that said rotary-part in each rotation moves the vibratory-member to bring the latch-member 130

ber into a position wherein further rotation of said part causes it to strike against the latch-member to unlatch the brake-member; and means driven by the sound-reproducer as it plays across the record which returns the vibratory- and latch-members to the position from which they were moved as aforesaid by the rotary-part.

4. In combination with a sound-reproducing machine having a motor-driven record-support and traveling sound-reproducer, an automatic stop comprising a vibratory-member; a brake-member movably connected with said vibratory-member; a latch-member arranged to latch the brake-member to the vibratory-member in its out-of-braking position; said latch-member extending in adjacent relation to the aforesaid vibratory-member; means which impels the brake-member into its braking-position when the latch-member is unlatched; a motor-driven rotary-part related both to the vibratory-member and to the latch-member so that said rotary-part in each rotation moves the vibratory-member to bring the latch-member into a position wherein further rotation of said part causes it to strike against the latch-member to unlatch the brake-member; means driven by the sound-reproducer as it plays across the record which returns the vibratory- and latch-members to the position from which they were moved as aforesaid by the rotary-part; and spring-means which is engaged by the aforesaid sound-reproducer driven-part only when the sound-reproducer is near the beginning of the record and which then yieldingly impels the vibratory- and latch-members in the same direction that they are impelled as aforesaid by the sound-reproducer driven-part.

5. In combination with a sound-reproducing machine having a motor-driven record-support and traveling sound-reproducer, an automatic stop comprising a reciprocatory-member; an operatively-supported brake-member; a latch-member carried with the reciprocatory-member for latching the brake-member in its out-of-braking position; means which impels the brake-member into its braking position when the latch-member is unlatched; a motor-driven part related both to the reciprocatory-member and to the latch-member so that during each cycle of its movement it moves the reciprocatory-member to carry the latch-member into a position wherein further movement of the motor-driven part causes it to disengage the latch-member to release the brake-member; means driven by the sound-reproducer as it plays across the record which returns the reciprocatory- and latch-members to the position from which they are moved as aforesaid by the motor-driven part; and means which is engaged by the aforesaid

sound-reproducer driven-part only when the sound-reproducer is near the beginning of the record and which then yieldingly impels the reciprocatory- and latch-members in the same direction that they are impelled as aforesaid by the sound-reproducer driven-part.

6. In combination with a sound-reproducing machine having a motor-driven record-support and traveling sound-reproducer, an automatic stop comprising a pivoted-member; a brake-lever pivoted to the pivoted-member; a latch-member arranged to latch the brake-lever to the pivoted-member with said brake-lever in its out-of-braking position; a motor-driven part related both to the pivoted-member and to the latch-member so that during each cycle of its movement it swings the pivoted-member to carry the latch-member into a position wherein further movement of the motor-driven part causes it to disengage the latch-member to release the brake-member; and a slide driven by the sound-reproducer as it plays across the record having a pin and slot frictional connection with the brake-lever to return the pivoted-member and the latch-member to the position from which they are swung as aforesaid by the motor-driven part, the end of said slot contacting with the pin to operate the brake-lever into its latched non-braking position when the sound-reproducer is moved beyond the edge of the record-support.

7. In combination with a sound-reproducing machine having a motor-driven record-support and traveling sound-reproducer, an automatic stop comprising a pivoted-member; a brake-lever pivoted to the pivoted-member; a latch-member arranged to latch the brake-lever to the pivoted-member with said brake-lever in its out-of-braking position; a motor-driven part related both to the pivoted-member and to the latch-member so that during each cycle of its movement it swings the pivoted-member to carry the latch-member into a position wherein further movement of the motor-driven part causes it to disengage the latch-member to release the brake-member; and a slide driven by the sound-reproducer as it plays across the record having a frictional connection with the brake-lever to return the pivoted-member and the latch-member to the position from which they are swung as aforesaid by the motor-driven part; and a spring between the pivoted-member and the slide whereby when the sound-reproducer is near the beginning of the record but not otherwise said slide through said spring yieldingly swings the pivoted-member and the latch-member in the same direction that they are swung as aforesaid by said slide when driven by the sound reproducer.

8. An automatic stop for sound-reproduc-

ing machines of the type comprising a motor-driven record support and a traveling sound-reproducer, the combination of a brake-member for actuating a brake normally tending to act to stop the record support, a controlling member pivotally connected to the brake member, a latch to connect the brake member and controlling member, the controlling member and latch being arranged to reciprocate in unison about the pivotal connection of the controlling member as a center, the latch, when engaged, acting to immovably connect the controlling member and brake member and thus restrain the brake, a motor-driven member active on the controlling member to move it in one direction and to thus set the latch in position to be tripped by said motor-driven member and to thus release the brake for action, and means operative by the sound-reproducer while the same is traveling across the record to move the controlling member in a reverse direction to avoid tripping of the latch by the motor-driven member.

25 9. An automatic stop for sound-reproducing machines of the type comprising a motor-driven record support and a traveling

sound-reproducer, the combination of a brake member carrying a brake normally tending to act to stop the record support, a controlling member pivoted relatively to the brake member, a latch connected to the brake member and adapted to engage the controlling member to prevent relative rotation between the controlling member and brake member and thus restrain the action of the brake, the controlling member and latch being mounted for limited reciprocatory movement, a motor-driven device for intermittently moving the controlling member in one direction to bring the latch into position to be tripped by said device, and means operative by the sound-reproducer while it is traveling across the record to move the controlling member in a reverse direction to avoid tripping of the latch by said device, said means being also operative upon return movement of the sound-reproducer to relatch the brake in non-active position.

In testimony whereof, I, said ROBERT HEAD, have signed my name to this specification this 19th day of October, 1918.

ROBERT HEAD.
